United States Patent Office.

AUGUSTUS BALL DAVIS, OF PHILADELPHIA, PENNSYLVANIA.

Letters Patent No. 106,129, dated August 9, 1870.

IMPROVEMENT IN DUPLEX WRENCH.

The Schedule referred to in these Letters Patent and making part of the same

I, AUGUSTUS BALL DAVIS, of Philadelphia, county of Philadelphia, State of Pennsylvania, have invented an Improved Duplex Wrench, of which the following is a specification.

Nature and Object of the Invention.

My invention relates to certain improvements in the duplex wrench for which Letters Patent were granted to me on the 24th day of August, A. D. 1869; and

My improvements consist—

First, of a peculiar construction, described hereafter, of the movable jaw, for the purpose of imparting strength to the same.

Second, of a nut adapted to the screw-stem of the wrench, and confined between a rounded top and bottom of a recess formed in the movable jaw, so that the said nut may not interfere with the free play of the jaw, as fully explained hereafter.

Third, of the combination of a serrated or toothed portion of the permanent jaw with a plain inclined portion of the movable jaw, so that a round object can be more firmly gripped than by the jaws described in my aforesaid patent.

Description of the Accompanying Drawing.

Figure 1 is a perspective view of my improved wrench;

Figure 2, an edge view;

Figure 3, a side view, partly in section;

Figure 4, a sectional plan, on the line 1 2, fig. 3;

Figure 5, a perspective view of the movable jaw of the wrench; and

Figure 6, a sectional plan, illustrating a modification of part of my invention.

General Description.

A is the stem of the wrench;

B, the handle;

D, the permanent jaw; and

E, the movable jaw.

On the rounded edges of the flat stem is formed a screw-thread adapted to a nut, f, which is confined within a recess, d, made in the lower portion of the movable jaw, the top and bottom of this recess being rounded, as shown by the dotted lines x x in fig. 3, for a purpose explained hereafter.

In my aforesaid patent of August 24, 1869, the opposite ends of the movable jaw were connected together by two curved legs of barely sufficient strength and rigidity to resist the strains to which the jaw had to be subjected. In order to obviate this defect, I make the jaw with a thin web, w, on each side, so as to form a hollow box-like casting, the webs, although comparatively light, affording the most efficient me-

dium, and the most advantageous disposal of metal, for resisting the strains to which the jaw has to be subjected.

The webs w w may be lightened by holes, m, of any desired shape; or the jaw may be rendered lighter by an opening, n, in one edge, as shown in fig. 5; or there may be a web, w', on one side only, as shown in fig. 6, the opposite side of the jaw being entirely open, or having simple strengthening-ribs, v; or the upper and lower ends of the jaw may be connected together by two webs, between which intervenes a clear open space.

The movable jaw is so adapted to the screw-stem A as to slide freely thereon without any lateral play, but so that the jaw may have a slight longitudinal play below on the stem, and more play above, as best observed on reference to fig. 3.

A pocket is formed within the movable jaw, for the reception of a spiral spring, f, which, bearing against a small pin, h, forces the latter against one edge of the screw-stem A, and tends to maintain the opposite edge in contact with the end p of the slot q in the top of the jaw, the slot being of sufficient length to permit a limited longitudinal play or vibration of the jaw on the stem. The freedom of this play is in no way interfered with by the nut F, owing to the rounded top and bottom, x x, of the opening within which the nut is confined.

The portion e of the permanent jaw, and the portion e' of the movable jaw, constitute that part of the wrench which is adapted to ordinary nuts, screw-heads, and other square or many-sided objects, while the portion i of the permanent jaw, and the portion i' of the movable jaw, are devoted to round objects, such as pipes, rods, &c.

On applying this portion of the instrument to the round rod j, and moving the handle in the direction of the arrow 1, fig. 3, the lower jaw will be moved in the direction of the arrow 2, while the rod is firmly jammed between the serrated under side of the portion i of the permanent jaw D and the inclined upper edge of the portion i' of the movable jaw E, after which the wrench cannot be moved further in the direction of the arrow 1 without turning the said rod j.

In my former patent, both the under side of the permanent jaw and the upper inclined side of the movable jaw were shown and described as notched or serrated; but I have found in practice that a much more perfect grip can be obtained by forming inclined teeth on the under side of the upper jaw only, the inclined upper side of the movable jaw being perfectly plain. It is important, however, that the serrations or teeth of the upper jaws should be inclined in the direction of the arrow 3.

A defect in the wrench described and illustrated in my former patent was its weakness at the junction of

the stem with the permanent jaw. This defect I overcome by means of a fillet, *t*, fig. 3, which affords the desired strength without interfering with the effective operation of the instrument on round rods, pipes, &c., and without rendering the instrument heavy and clumsy.

A recess, *t'*, is made in the upper end of the movable jaw, for receiving the whole or a portion of this fillet.

Additional strength may be imparted to the stem at its junction with the permanent jaw, by a fillet, *y*, on each side of the stem, the slot in the upper part of the movable jaw being countersunk to receive these fillets.

Claims.

1. The vibrating and sliding jaw *E*, having on one

or both sides a thin web, as set forth.

2. A nut, *F*, adapted to the screw-stem *A*, and confined between the rounded top and bottom, *x x*, of a recess in the movable jaw *E*, as specified.

3. The combination of the serrated or toothed portion *i* of the permanent jaw with the plain inclined portion *i'* of the movable jaw.

In testimony whereof I have signed my name to this specification in presence of two subscribing witnesses.

AUGUSTUS BALL DAVIS.
